WORKMAN'S TIME RECORDER

Ernest A. Faller, Brooklyn, N. Y., assignor to International Business Machines Corporation, New York, N. Y., a corporation of New York

Application January 27, 1940, Serial No. 315,955

9 Claims. (Cl. 234—41.5)

This invention relates to improvements in time recorders for recording the time of the arrival and departure of each of a number of employees and, more particularly, relates to improvements in recorders of that type wherein each employee is assigned an individual key, which upon being operated at the beginning and end of a period of time, causes a permanent record to be made upon a suitable record sheet.

One object of the instant invention is the provision of novel means controlled by a plurality of keys to initiate a rotation of a printing drum to selectively stop the rotation of said drum.

Another object is the provision of novel means to release the depressed keys.

Another object of the invention is the provision of novel means operated when the drum is stopped to effect a printing operation.

The instant invention is adapted to be applied to a recorder of the type disclosed in U. S. Patent No. 522,784 issued July 10, 1894, to John Dey. In known recorders of this type it has been necessary for the operator to rotate a lever to select a position, and then depress to effect a recording. The present invention contemplates the provision of an individual key for each employee and automatic mechanism responsive to the depression of said keys for selectively recording the employees' time of arrival and departure.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a front elevation of the recorder.

Fig. 2 is a sectional view taken approximately along the line 2—2 of Fig. 1.

Fig. 3 is a detail view of two of the keys in their normal position.

Fig. 4 is a detail view of the same two keys, one of them now being in the depressed position.

Fig. 5 is a detail view showing the means for latching the keys in their depressed position.

Fig. 6 illustrates the means for locking the keys against depression.

Fig. 7 is a detail sectional view of the drum control arm taken approximately along line 7—7 of Fig. 2.

Fig. 8 is a detail view of the mechanism for operating the print magnet contacts.

Fig. 9 is a detail view of a part of the mechanism for locking the keys against depression during the minute advance of the typewheels.

Fig. 10 is a schematic circuit diagram.

In accordance with a preferred embodiment of the invention as shown in the drawings, the mechanism is enclosed in a casing 21 mounted

on a base 22. A drum 23 (Fig. 2), upon which is carried the record sheet 24, is mounted on a hollow shaft 25 journaled in frames 26 and 27 which are secured to the base 22. The drum 23 is rotated by a motor 28 mounted on the base 22, the motor driving a shaft 29 by a belt 30 and suitable pulleys. A worm gear 31 on the shaft 29 meshes with a gear 32 frictionally carried between plates 33 and 34 secured to an enlarged portion of a hub 35 fast on the hollow shaft 25. A spring 36 presses the plate 34 against the gear 32 and the gear 32 against the plate 33. Thus the rotation of gear 32 by the motor 28 frictionally drives the drum 23.

The rotation of the drum 23 is initiated and controlled by keys 37 of which 100 are provided in this illustrative embodiment of the invention. It is to be understood that a greater or lesser number of keys may be provided depending upon requirements.

The keys 37 are slidably mounted in a circular member 38 secured to the front of the casing 21. Secured to this member is an annular bracket 39 supporting a ring 40 against the periphery of which the inner ends of the keys 37 are pressed by springs 41. Each of the keys 37 carries a projection 42 which, upon depression of a key, latches over the ring 40 to retain the key in its depressed position (Fig. 5).

Depression of any one of the keys 37 operates mechanism which energizes the motor 28 to rotate the drum 23. Loosely mounted on a stud 43 (Figs. 1 and 2) projecting from the bracket 39 is a disc 44 having an offset portion 45 cooperating with the inner ends of the keys. Upon depression of a key 37, a cam surface 51 on the key then engages the portion 45 of the disc 44 and rocks said disc clockwise as viewed in Fig. 1. At this movement, a roller 52 carried by but insulated from the ring 40 engages contacts 53 and 54 (see also Fig. 10) completing a circuit from the battery 55, contacts 53 and 54, motor 28 back to battery 55. The motor thus energized rotates the drum 23 in a counterclockwise direction (Fig. 1) until arrested by the inner end of a depressed key 37 by the following described mechanism:

Integral with the hub 35 (Fig. 2) is an arm 56 which pivotally carries an arm 57. The end of the arm 56 is bifurcated and cooperates with a projection 58 on the arm 57. A spring 59 holds the projection 58 against the left-hand fork of the arm 56 as viewed in Fig. 7. As the arm 56 rotates counterclockwise (see also Fig. 8) the free end of the arm 57 strikes the end of a depressed key 37, the arm 56 continuing its travel so as to rock the arm 57 clockwise about its pivot until the right-hand fork of arm 56 strikes the projection 58, thus arresting the arm 56 and drum 23 in the position selected by the particular key 37 depressed.

Clockwise movement of the arm 51 closes a pair of contacts 60 establishing a circuit from the battery 55, a brush 61, a conducting ring 62 which is carried by but insulated from the arm 56, contacts 60, a conducting ring 63, a brush 64, print magnet 65, and back to the battery 55. The brushes 61 and 64 are mounted on the frame 26. This energizes print magnet 65 to take an impression from printing wheels 66 on the record sheet 24, the printing wheels being operated by 10 any suitable clock mechanism in a well known manner to be described briefly hereinafter.

As soon as the print is made it is desired to release the key which controlled the stopping of the drum 23. This is effected under the control 15 of the print magnet 65. Energization of this magnet closes contacts 66 (Figs. 2 and 10) establishing a circuit from battery 55, a solenoid 67, contacts 66 back to the battery. Referring now to Fig. 2, the solenoid 67 is mounted on the frame 27 and its armature 68 is carried on a rod 69 extending through the hollow shaft 28. At its opposite end the rod 69 cooperates with a bell crank 70, the other arm of which projects into a slide 71 mounted in brackets 72 secured to the arm 56.

When energized the solenoid 67 attracts its armature 68 thrusting the rod 69 to the left as viewed in Fig. 2. This rocks the bell crank 70 clockwise and thrusts the slide 71 radially outward. When the arm 56 was stopped by the depressed key, the outer end of the slide 71 came to rest directly in line with the inner end of the key, and thus the outward movement of the slide disengages the projection 42 from the ring 48 (see Figs. 5 and 7), whereupon the spring 41 returns the key to its normal position.

If no other key is depressed the arm 56 and the drum 23 remain in the position to which they were adjusted since the key has been returned to normal so as to permit a spring 73 (Fig. 1) to restore the disc 44-45, moving it in a counter-clockwise direction so as to remove the roller 52 from its operated position between the contacts 53-54. The resultant opening of contacts 53-54 breaks the circuit to the motor 28. Assume that a plurality of keys 37 are depressed, for instance, key numbers 8, 16, 17, 40, and 80, and that the last key registered was No. 5. The arm 56 and drum 23 will first go to the "8" position and print the time as described above. The "5" key will be released and returned to normal; however, as long as another key is depressed the disc 44-45 remains out of normal position thus maintaining the motor 28 energized. The motor therefore does not stop but moves the drum 23 and arm 56 successively to each position represented by a depressed key stopping the drum and printing the time at each station until the last depressed key has been restored to undepressed position whereupon, as set forth above, the disc 44-45 is restored stopping the motor.

It is to be pointed out that the recording does not occur in the same sequence in which the keys were depressed but in their numeric sequence as the drum 23 and its control arm are selectively rotated in a clockwise direction. The keys may be depressed in rapid sequence by workmen upon their arrival or departure and the recording mechanism then automatically proceeds to make the proper time records. The delay and inconvenience in the manual operation of the dial in the dial recorders familiar in the art is thus eliminated. In addition, it has in common with prior dial recorders the advantages over card operated

recorders in that the latter require a certain amount of time for removal of a card from a card rack, insertion of the card to obtain the print, withdrawal of the card from the printing position and replacing it in its proper position in the card rack. Though the time saving for each recording operation is rather inappreciable, it does accumulate to the extent of becoming an important advantage in handling long lines of workmen passing the clock during the more predominant periods of arrival and departure.

As each key is depressed, a contact 74 thereon wipes by a conductor ring 75 mounted on but insulated from the bracket 39 and common to all of the contacts 74, making a momentary contact of sufficient duration to energize a magnet 76. Energization of magnet 76 is arranged to cause one tap on the single stroke bell 77. No connection is made between contact 74 and ring 75 when the key is restored for the reason that the slide 71 has moved the inner end of the key radially outwardly a distance sufficient to cause the contact 74 to clear the ring 75 as the key is restored (see Fig. 5 dotted line position of key).

The typewheels 66 (Fig. 2) are advanced by a clock 78 suitably mounted in the bracket 39. A shaft 79, driven by the clock mechanism, extends upwardly therefrom and at its upper end is provided with a beveled gear 80. This gear meshes with a beveled gear 86 on a horizontal shaft 87. Between the frames 28 and 27 the shaft 87 is square and slidably carries a pinion 88 meshing with a gear 89 which advances the printing wheels 66. Structure of this nature is old in the art and further description is therefore deemed unnecessary.

The printing mechanism is enclosed in a casting 90 and is slidably mounted on two rods 91 extending between the frames 28 and 27. The entire printing unit may thus be shifted laterally, as from front to back of the drum 23, according to various columns on the record sheet in order to record in these columns the "in" and "out" time of each of the various employees. The device for shifting the printing mechanism does not form a part of the instant invention and for this reason is not disclosed. One of several well known devices may be utilized for this purpose and may be manually operated or automatically controlled in accordance with time.

Printing is effected by the magnet 65 acting through a lever 92 which also closes the previously mentioned contacts 66. Operation of the lever 92 drives the typewheels against the drum 23 making an impression on the record sheet 24 by means of an ink ribbon 93. The ink ribbon is wound and unwound from spools 94 and 95 by any suitable ribbon feeding and reversing mechanism. The spools 94 and 95 are mounted in brackets 96 and 97 respectively which are secured to the frames 26 and 27.

In order to prevent depression of any key during the time the clock advances the typewheels 66, a solenoid 98 (Figs. 1, 2, and 10) is provided, which is energized during the time the typewheels are being advanced by a cam 99 on the seconds arbor of the clock. The cam 99 thus receives one rotation each minute closing contacts 100 and energizing the solenoid 98 just before the clock shifts the printing wheels to the next minute. The contacts 100 are broken immediately after the typewheels have been advanced.

The armature 101 of the solenoid 98 is provided with teeth 102 which mesh with a pinion 103 on

a shaft 104 which, at its opposite end carries a pinion 105 meshing with teeth in a ring 106. This ring is mounted to oscillate under the influence of the solenoid 98. When energized the solenoid 98 attracts its armature 101 rotating the pinion 103, shaft 104 and pinion 105 counter-clockwise as viewed in Fig. 1, thus rotating the ring 106 also in a counterclockwise direction. The ring 106 is provided with a series of notches 107 displaced around its periphery. Each of the notches 107 is adapted, when said ring is shifted by the solenoid 98, to cooperate with corresponding projections 108 on an adjacent ring 109. The ring 109 does not rotate but is slidably mounted on a series of studs 110 projecting from the outer flange of the bracket 39 and the projections 108 are pressed against the ring 106 by springs 111. When, as set forth above, the ring 106 is rotated the notches 107 come into alignment with the projections 108 permitting the springs 111 to move the ring 109 bodily toward the front of the machine, or toward the left as viewed in Figure 2.

Pivotedly supported on brackets 112 adjacent each key 37 is a lever 113 provided with a projecting arm 114 which is normally pressed against the ring 109 by a spring 115. When the ring 109 moves to the left the springs 115 rock the levers 113 counterclockwise (Fig. 6) to position the ends of said levers in the paths of projections 116 on the keys 37 thus preventing depression of any of the keys during the time the typewheels 66 are being advanced.

When the contacts 100 are opened so as to deenergize solenoid 98, a spring (not shown) restores the ring 106 to normal, camming the ring 109 toward the right (Fig. 2). At this movement of the ring 109 engages the arms 114 on levers 113 rocking said levers out of the paths of the projections 116 on the keys 37 thus freeing the keys for depression.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a workman's time recorder, the combination of a clock controlled printing means, a rotatable drum to support a record material, a selector arm rotatable with the drum, a plurality of keys to selectively arrest the selector arm and drum, and means controlled by the selector arm to effect printing when said arm is arrested.

2. In a workman's time recorder, the combination of a clock controlled printing means, a drum to support a record material, a selector arm, said arm and drum being rotatable in unison, depressible keys to selectively arrest the arm and drum, means integral with the selector arm and operated when said arm is arrested by a depressed key to effect printing, and means operated by the print effecting means to release the depressed key.

3. In a workman's time recorder, the combination of a clock controlled printing mechanism, a drum and a selector arm associated therewith,

power means to frictionally drive the drum, depressible keys to selectively arrest the drum, means on the arm effective when said arm is arrested by a depressed key to effect printing, and other means on said arm controlled by the printing means to release the depressed key.

4. In a workman's time recorder, the combination of a printing drum, a selector arm associated with the drum, power means to frictionally drive the drum, depressible keys to selectively stop the drum, key release means controlled by the selector arm, and means common to all of the keys to energize the power means and to maintain said power means energized until all of the depressed keys are released.

5. In a workman's time recorder, the combination of printing mechanism, a printing drum, a selector arm associated with the drum, power means to frictionally drive the drum and the selector arm, a plurality of keys each operable to stop the drum in a different position, means carried by the selector arm to control the printing means, means operated under control of the printing mechanism at each of the arrested positions of the drum to release the operated key which stopped the drum at said position, and a member responsive to all of the operated keys to energize the power means and to maintain said power means energized until all of said operated keys are released.

6. In a workman's time recorder, the combination of a printing mechanism, a printing drum, a selector arm associated with the drum, means to frictionally drive the drum, a plurality of operable keys to successively stop the drum, and means operated when the drum is stopped by an operated key to effect an operation of the printing mechanism.

7. In a workman's time recorder, the combination of a printing mechanism, a printing drum, a selector arm associated with the drum, means to rotate the drum and the selector arm, a plurality of depressible keys to successively stop the selector arm and the drum, means operated when the arm is stopped by a key to effect an operation of the printing mechanism, and means operated under the control of the printing mechanism to release the depressed key.

8. In a workman's time recorder, the combination of a printing mechanism, a printing drum, means to drive the drum, a plurality of depressible keys to successively stop the drum in different positions, means commonly actuated by depression of any one or a number of said keys to energize the drive means and to maintain the drive means energized until all of the depressed keys are released, means operated as the drum is successively stopped at a different position by each depressed key to effect an operation of the printing mechanism, and electromagnetic means energized under the control of the printing means to release the depressed key for said drum position.

9. In a workman's time recorder, the combination of a printing mechanism, a rotatable printing drum, a plurality of keys individually operable to selectively control the position of the drum, means operated as the drum arrives at each position selected by an operated key to effect an operation of the printing mechanism, and key release means rotatable with the drum and operated by the printing means to release the operated key for said drum position.

ERNEST A. FALLER.
